SUCKER ROD STRIPPER

Charles S. Crickmer, Dallas, Tex.

Application May 2, 1941, Serial No. 391,457

4 Claims. (Cl. 286—16)

This invention relates to new and useful improvements in sucker rod strippers.

One object of the invention is to provide an improved sucker rod stripper having flexible means for frictionally engaging the pump or sucker rods to remove the oil or well liquid therefrom as the same are withdrawn from the well tubing, whereby said rods are cleansed and undue waste of the well liquid is prevented.

An important object of the invention is to provide an improved sucker rod stripper having a flexible stripping element of relatively simple and inexpensive construction removably supported therein, whereby the element may be readily removed and replaced economically when the same becomes worn.

Another object of the invention is to provide a sucker rod stripper having an improved annular stripping element of resilient material which is molded or otherwise permanently secured within a housing and which has its bore of a diameter slightly less than the outer diameter of the sucker rods so as to snugly engage and scrape oil from the same; the element and housing providing an inexpensive unit which may be entirely discarded when the element becomes worn.

A particular object of the invention is to provide an improved stripping element, of the character described, having grooves formed in its upper and lower surfaces for increasing the flexibility thereof, whereby the passage of couplings or tool joints therethrough is facilitated.

A further object of the invention is to provide an improved sucker rod stripper, of the character described, wherein the stripping element is composed of a pair of semi-circular resilient segments and each segment is molded within one of the semi-cylindrical sections of a housing, whereby the stripper may be readily installed in operating position; the molding of said element in individual semi-circular segments within each housing section forming integral resilient lips on the vertical edges of the sections so as to seal the joint therebetween and obviate the necessity of additional packing.

Still another object of the invention is to provide an improved sucker rod stripper which includes a housing composed of semi-cylindrical sections for supporting the stripping element, the sections being pivotally or removably connected together so as to permit the removal of said element from the housing and also to facilitate positioning of the housing around said rods, as well

as removal therefrom, when said sections are swung or separated.

The construction designed to carry out the invention will be hereinafter described together with other features of the invention.

The invention will be more readily understood from a reading of the following specification and by reference to the accompanying drawings, as an example of the invention is shown, and wherein:

Figure 1 is a transverse, vertical, sectional view of a sucker rod stripper, constructed in accordance with the invention.

Figure 2 is a view, similar to Figure 1, showing a coupling of the sucker rod passing through the stripping element of the stripper.

Figure 3 is a horizontal, cross-sectional view, taken on the line 3—3 of Figure 1.

Figure 4 is a transverse, vertical, sectional view, showing a modified form of stripping element.

Figure 5 is a plan view of the stripper shown in Figure 4.

Figure 6 is a plan view of a modified form of stripping element.

Figure 7 is a view, similar to Figure 1, showing a plurality of stripping elements molded within a nipple.

Figure 8 is a view, partly in elevation and partly in section, of another form of stripper having a slightly modified form of stripper element mounted therein.

Figure 9 is a plan view of the stripper shown in Figure 8.

Figure 10 is a horizontal, cross-sectional view, taken on the line 10—10 of Figure 8, and

Figure 11 is a horizontal, cross-sectional view, taken on the line 11—11 of Figure 8.

In the drawings, the numeral 10 designates an upright cylindrical body or nipple which has its lower end externally screw-threaded as shown at 11 so that it may be connected to the upper end of a well tubing 12 by a suitable coupling collar 13. The bore 14 of the nipple is of a diameter

45 substantially equal to the bore of the tubing and communicates with the same. Although the nipple may be cylindrical, it is preferable to split the same diametrically so as to provide complementary semi-cylindrical sections 17 (Figure 3). For removing oil from the sucker rods 15 which extend axially through the tubing 12, a flexible stripping element 18a is disposed within the bore of the nipple 10 adjacent its upper end.

The element may be composed of an annular disk, but it is preferably formed of a pair of

semi-circular segments 18, of rubber, neoprene, or other suitable resilient material, which sections co-act to provide a resilient collar or ring. The external diameter of the collar is substantially equal to the diameter of the nipple bore 14, whereby the external periphery of said collar snugly engages the wall of said bore. The collar is relatively thick and one segment thereof is secured within each nipple section 17 by having its external arcuate surface bonded, molded or otherwise fastened, to the inner wall of its respective section. An arcuate lip 19 is made integral with each of the upper and lower faces of each segment at their outer or marginal edges so as to provide an amplified bonding surface for reinforcing the segments. The inner surfaces of the lips 19 are curved or arced inwardly, whereby said lips form a continuation of the upper and lower faces of the segments. It is preferable that the bore 20 of the collar, which is formed by the inner arcuate surfaces of the segments, be equal to or slightly less than the diameter of the rods 15 which extend therethrough, whereby said disk will frictionally engage said rods.

During the molding of the segments 18, it has been found practicable to form an integral lip or projection 21 on the vertical edges of each section 17 at the same time. This is done by permitting a small portion of the rubber, or other material used, to escape from the mold (not shown) and flow onto the vertical edges of each section to which it adheres. The lips 21 extend throughout the length of the edges of the segments 18 and are relatively thin or film-like, whereby the same will fill the space of the material removed by splitting the nipple and will co-act to seal off the joint between the abutting surfaces of the sections when the same are brought together in operating position. Obviously, the provision of the lips or projections 21 eliminate the necessity of separate packing strips for sealing the joints of the nipple. For increasing the efficiency of the stripping element, the end surfaces of the segments are bevelled or inclined at an angle to the vertical, as indicated by the numeral 22 in Figures 3 and 4. It is preferable to incline the end surfaces of each segment in opposite directions, whereby one end surface is directed upwardly and inwardly and the other upwardly and outwardly. Thus, the abutting end surfaces of the segments will be complementary and will co-act to seal off the joint therebetween as well as to reinforce each other and prevent undue distortion thereof.

Whenever it is desirable or necessary to withdraw the rods 15 from the tubing 12, the nipple 10 is screw-threaded into the uppermost coupling collar 13 of said tubing immediately prior to such withdrawal. The rods are then pulled upwardly through the bore 20 of the collar 18, whereby an excessive amount of oil or other liquid clinging to said rods will be stripped or wiped therefrom by the inner periphery of said collar. This removed oil or liquid will, of course, flow downwardly into the tubing. When a joint or coupling collar 25 of the rods is encountered, the resiliency of the collar 18 will permit the inner portion of the same to flex upwardly as shown in Figure 2. After the joint has passed through the disk, it is obvious that the same will revert to its original position (Figure 1). However, there will be a slight upward flexing of the disk whenever the rods are moved upwardly due to the small diameter of the bore 20.

Since the nipple 10 and stripping element 18a

are formed as a unit and are relatively inexpensive to manufacture, the same may be discarded whenever said element becomes worn. In order to replace this stripper, it is only necessary to disconnect the nipple from the collar 13 and connect the nipple of a new stripper to said collar. Thus, the stripper may be readily and economically replaced at any time. Due to the simple construction of the stripper, the manufacture of the same is relatively inexpensive.

For increasing the flexibility of the stripping element, a plurality of concentric, annular grooves or channels 23 may be formed in the upper and lower faces of the collar as shown in Figures 4 and 5. The provision of these grooves will more readily permit or facilitate flexing of the collar, especially when the same is engaged by one of the couplings 25, or other enlargements, of the rods 15. It is manifest that substantially the same result could be obtained by the formation of radial channels or recesses 24 in the upper and lower faces of the collar (Figure 6). Although neither the grooves 23 nor the channels 24 are essential, both are desirable since they do not materially weaken the stripping element.

As shown in Figure 7, a plurality of stripping elements may be mounted within the bore of a nipple in spaced superimposed relation. Each element consists of a pair of semi-circular segments 26 which have arcuate lips 21, similar to the lips 19, formed on their upper and lower surfaces. Instead of being inclined or bevelled, the end surfaces may be vertical so as to terminate substantially flush with the edges of the nipple sections 17. For sealing the joint between the adjacent surfaces of abutting segments, one end surface of each segment is provided with a longitudinally-extending tongue 28, while a complementary groove or recess 29 is formed in the other end surface. When the sections 17 of the nipple are brought together in operating position, the tongues of the segments will engage within the grooves thereof and co-act to seal the joint therebetween. The tongue and groove connections will also tend to prevent undue distortion of the segments in the same manner as the bevelled or inclined surfaces of the segments 18. In molding the segments 26, the sealing lips or projections 21 are formed on the vertical edges of the sections 17 of the nipple, as has been hereinbefore described.

A modified form of stripper is shown in Figures 8 to 11 and includes a cylindrical housing or casting 30 having a depending, reduced shank 31 which is adapted to be screw-threaded into the coupling collar 13. The central or intermediate portion of the housing 30 is enlarged to provide an annular recess or groove 32 within the bore 33 thereof, while the upper end of said housing is curved inwardly, upwardly and then outwardly so as to form a flared collar or top 33a. The housing is preferably composed of a pair of complementary semi-cylindrical sections or halves 34 having radially-projecting lugs or ears 35 which co-act with pins 36 to provide hinges for fastening the sections together.

The stripping element of this stripper is formed of an annular disk or collar 37, similar to the disk 18a, having integral annular lips 38 and an axial bore 39 which are substantially identical to the lips 19 and bore 20 of said disk 18a. The disk 37 is of an external diameter greater than the disk 18a and has its outer peripheral surface bonded, molded or otherwise secured, to the inner periphery of a metallic supporting col-

lar or ring 40, whereby the stripping element may be supported within the recess 32 of the housing. In order to facilitate the insertion and removal of the stripping element from around the sucker rods 15, the disk and ring are split at an incline from a vertical plane, as indicated by the numerals 41 and 42, respectively. Thus, the free ends of the disk and ring may be readily separated or sprung apart so as to engage the stripping element around the rods 15.

When the stripping element is disposed within the recess 32 of the bore 33 of the housing, the central portion of its joint is preferably aligned with one of the joints of said housing as shown in Figures 9 and 10. For holding the stripping element fixed in this position, diametrically-opposed screw-threaded openings 43 are formed in the ring 40. Suitable stud bolts or screws 44, which extend through openings 45 in the housing wall, engage within the openings 43 so as to prevent rotative movement of the stripper element within the housing. Therefore, whenever the sections of the housing are swung apart, the free ends of the stripping element will be moved away from each other and thereby permit the removal of the entire stripper while the rods are extending therethrough. For preventing leakage of the housing joints, vertical packing members or strips 46, of suitable material, are interposed between the abutting faces of the shanks of the housing sections 34 as shown in Figure 11. The packing members may be mounted in any suitable manner, but it is preferable to dispose of one of the adjacent faces of each section 34. As shown in Figure 8, each recess 47 extends from the intermediate portion of the shank of its section to the recess 32 and follows the contour of said shank.

In operation, the housing 30 of the stripper is attached to the uppermost coupling collar 13 of the well tubing. The sucker rods 15 are then pulled upwardly through the bore 39 of the disk 37 in the usual manner, whereby the excess oils or other liquid clinging to said rods will be wiped therefrom. In order to replace the stripping element, it is necessary to disconnect the shank 31 of the housing from the collar 13 and then disengage the bolts 44 from the ring 40 of said housing. By removing one of the pins 36, the sections 34 may be swung apart and the stripping element lifted from the same and another substituted in its place.

If it is necessary or desirable to replace the stripper element while the rods are extending through the bore of the stripper, the housing shank is disconnected from the collar 13 in the same manner. The sections of the housing are then swung apart, such swinging being permitted by the removal of the pin 36 which is immediately adjacent the joint or split of the stripping element. Since the ring 40 is connected to both of the sections 34, the stripping element will be swung apart by the outward movement of said sections to permit the passage of the rods through the joint of said element. The bolts 44 are then disengaged from the ring 40 and the element removed from the housing. After another stripping element has been positioned within the housing, the sections are again swung apart and the element spread for the reception of the rods. The sections are then fastened together by the pin 36 and the housing shank is screw-threaded into the collar 13, whereby stripping of the rods may be continued.

It is manifest that the stripping element may

be readily removed at any time, irrespective of whether the well rods are extending therethrough. This is made possible by the splitting of the stripping element and the fastening of the same to the sections of the housing. Of course, by splitting the element diagonally, the leakage of oil or other liquid is reduced to a minimum. Since the element is removably confined within the housing, it is relatively simple to replace the same.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A stripping device for a well rod including, 20 a housing composed of semi-cylindrical sections, and flexible means bonded to the internal wall of each section and co-acting with each other for engaging and surrounding the rod, the flexible means projecting beyond the internal wall of its section and being bonded to the vertical edges thereof so as to provide a sealing means between the edges of the sections when the same are placed together.

2. A stripping device for a well rod including, 30 a housing composed of semi-cylindrical sections, an arcuate yieldable member confined within each housing section to form a collar for engaging and surrounding the rod, the collar having a plurality of recesses in its upper and lower surfaces for 35 increasing the flexibility thereof to facilitate passage of enlargements on said rod, and arcuate lips formed on the upper and lower surfaces of each element at the external peripheral portion thereof so as to provide an amplified bonding surface, each element projecting beyond the interior of its section so as to overlie the vertical edges thereof, whereby a seal between the edges of the sections is provided when said sections are placed together.

3. A stripping device for a well rod including, 45 a pair of substantially semi-circular sections adapted to fit together to form an annular housing, a substantially semi-circular stripping element constructed of a resilient material bonded to the inner surface of each section, the material of which the element is formed also being bonded to the vertical edges of its section, whereby when the sections are placed together the material between the abutting vertical sections provides a packing or sealing means therebetween, the semi-circular stripping elements co-acting with each other to form an annular stripping member.

4. A stripping device for a well rod including, 60 a housing adapted to be removably connected to the upper end of a well tubing and composed of semi-cylindrical sections, a semi-circular resilient element having its external surface bonded to the inner wall of each section and co-acting with each other for engaging and surrounding the rod, the ends of each element being inclined in opposite directions and being complementary to the ends of the other element, whereby the abutting surfaces will coact to seal off the joint therebetween and reinforce each other, and a radial lip projecting outwardly from the exterior of each end of each element and overlying the vertical edges of its housing section so as to provide a seal between the sections when the same are placed together.

CHARLES S. CRICKMER.
